US00D981712S

(12) United States Design Patent (10) Patent No.: US D981,712 S
(45) Date of Patent: * Mar. 28, 2023

(54) HANDBAG HANDLE

(71) Applicant: J. Choo Limited, London (GB)

(72) Inventor: Johanna Cardenas, Paris (FR)

(73) Assignee: J. Choo Limited, London (GB)

() Term: 15 Years

(21) Appl. No.: 29/784,919

(22) Filed: May 21, 2021

(30) Foreign Application Priority Data

Dec. 8, 2020 (EM) 008312649-0004

(51) LOC (14) Cl. 03-01

(52) U.S. Cl.

USPC D3/246; D3/318

(57) CLAIM

The ornamental design for a handbag handle, as shown and described.

DESCRIPTION

FIG. 1 is a front perspective view of a handbag handle showing my new design;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

The broken lines in the figures depict environment that forms no part of the claimed design.

1 Claim, 7 Drawing Sheets
